UNITED STATES PATENT OFFICE

133,973

DESIGN FOR AN ELECTRIC DRILL UNIT OR THE LIKE

Oollo Lamb, St. Louis, Mo., assignor to Knapp-
Monarch Company, St. Louis, Mo., a corpora-
tion of Missouri

Application January 19, 1942, Serial No. 105,293

Term of patent 7 years

To all whom it may concern:

Be it known that I, Oollo Lamb, a citizen of the United States and a resident of St. Louis, in the State of Missouri, have invented a new, original, and ornamental Design for an Electric Drill Unit or the like, of which the following is a specification, reference being had to the accompanying drawing, forming a part thereof.

Figure 1 is a top plan view of an electric drill unit or the like, showing my new design;

Figure 2 is a side elevational view thereof;
Figure 3 is a front end elevational view there-
of; and

Figure 4 is a rear end elevational view thereof.
I claim:

The ornamental design for an electric drill unit or the like, substantially as shown.

OLLO LAMB.
